(57) **CLAIM**

The ornamental design for a combined table and refrigerator, as shown and described.

DESCRIPTION

FIG. 1 is a front elevational view of the combined table and refrigerator of the present invention;

FIG. 2 is a back elevational view of the combined table and refrigerator of FIG. 1;

FIG. 3 is a left side elevational view of the combined table and refrigerator of FIG. 1;

FIG. 4 is a right side elevational view of the combined table and refrigerator of FIG. 1;

FIG. 5 is a top plan view of the combined table and refrigerator of FIG. 1; and,

FIG. 6 is a bottom plan view of the combined table and refrigerator of FIG. 1.

The broken lines showing the cord are for illustrative purposes only and form no part of the claimed design.

The surface(s) or portion(s) of the article not shown in the drawing or described in the specification form(s) no part of the claimed design.
